ANIMAL NAIL CLIPPERS

Charles Laing, 11374 Schaefer Road, Detroit 27, Mich.

Filed June 22, 1959, Ser. No. 821,739

3 Claims. (Cl. 30—29)

2

as seen in Figures 1 and 2. On operation of the handle 6 by squeezing it towards the other handle 5 against the bias of the spring 11, the pivot arm 8 causes the blade 1 to slide over the holder 2 until it reaches the position 5 shown in Figure 3 with that portion of a nail which has been protruding above the hole 3 cut off.

In order to prevent undue penetration of the nail to be cut through the shaped hole 3 a gauge arm 13 is provided detachably mounted on the handle 5 by means of 10 a band 14 (see Figure 4) by a spring clip 15 (see Figure 5). The arm 13 is spaced just slightly apart from the upper surface of the nail holder so that a nail passing through the hole 3 will abut against the arm 13 and hence only a pre-determined amount of nail will be cut 15 off on operation of the handle 6.

In Figure 6 there is shown a modification in which the gauge arm is formed in the shape of a receptacle 16 to hold the nail cuttings. In this case a plate 17 projecting somewhat over the nail holder and blade, but leaving sufficient room for a nail to be passed through the hole to abut against the plate 17 until cut, after which the severed portion of the nail drops into the receptacle 16, provided to retain the cuttings within the receptacle.

It will be appreciated that as in both constructions 25 as the gauge arm is detachably mounted on the first handle by a simple push fit, arms arranged at various heights above the counter-knife may be provided to allow of different lengths of nails being cut. Alternatively the arm may be hingedly connected to the counterknife 30 holder and so arranged that it may be swung adjacent the hole in the nail holder and held there by means of a biased spring so as to limit the projection of a nail through the hole, e.g. to either $\frac{1}{16}$ " or $\frac{1}{16}$ ". Each projecting portion is then clipped off in the manner herein 35 described. If desired more than one hinging arm may be provided, each arm being differently dimensioned so that according to the amount of nail to be cut off, so one or other of the arms may be hingedly moved to operative position.

40 What is claimed is:

1. A nail clipper comprising a first handle, a nail holder extending from said first handle, an aperture in said holder for receiving nail to be cut, a blade arranged for sliding over the holder, so as to cut or slice off that portion of the nail projecting therethrough, a second handle pivotally connected to said first handle, spring bias means between said handles and a gauge arm mounted on said first handle in a position slightly spaced from the aperture in the nail holder to prevent undue penetration of a nail to be cut.

2. A nail clipper as claimed in claim 1 in which a link is pivotally attached at one end to the second handle and at the other to the blade, spring bias means comprising a spring positioned between the first handle and the pivot link to provide a bias normally to hold the blade in a retracted position.

3. A nail clipper as claimed in claim 1 in which said gauge arm is formed with a recess into which clipped nails can be housed.
